 American Can Company, New York, N. Y., a
 corporation of New Jersey

Application September 12, 1939, Serial No. 294,555

1 Claim. (Cl. 220—43)

The present invention relates to containers such as hinge cover tablet boxes or the like and has particular reference to a hinge cover having a raised cam edge which facilitates opening of the box.

An object of the invention is the provision in a tablet box and the like of a hinge cover wherein the edge of the cover adjacent its hinged edge is shaped in a raised curved cam section which permits the easy snapping open of the cover when a slight pressure is applied to the hinge edge of the box.

Numerous other objects and advantages of the invention will be apparent as it is better understood from the following description, which, taken in connection with the accompanying drawing, discloses a preferred embodiment thereof.

Referring to the drawing:

Figure 1 is a perspective view of a tablet box embodying the instant invention, the box being closed;

Fig. 2 is a rear elevation of the box shown in Fig. 1;

Figs. 3 and 4 are enlarged sectional views taken substantially along the line 3—3 in Fig. 2, the views showing the cover in different positions; and

Fig. 5 is a fragmentary sectional view similar to Figs. 3 and 4 and drawn to the same scale, the view being taken substantially along the line 5—5 in Fig. 2.

As a preferred embodiment of the invention the drawing illustrates a rectangular shaped, sheet metal tablet box which includes a body member 11 and a cover member 12 permanently connected by a floating pintle hinge 13. The body and cover members are preferably of one piece, shallow die-drawn construction.

The body member 11 comprises a flat bottom wall section 15 (Fig. 3) which at its outer edges merges into a continuous and surrounding upright wall which includes a front wall section 16, a rear hinge wall section 17, and a pair of connecting side wall sections 18. These wall sections are all of the same height with a straight terminal top edge 19.

The front wall section 16 of the body is formed with an outwardly extending cover locking node or projection 21. The body rear wall is provided with a pair of spaced and vertically elongated hinge lugs 22 (Figs. 2, 3 and 5) which are used in connection with the floating hinge 13 as will be hereinafter explained.

The cover member 12 preferably comprises a semi-flattened, dome-shaped top wall section 25

which at its outer edges merges into a continuous surrounding and depending flange which extends down adjacent to and on the outside of the body upright wall, when the cover is in place on the body member. The cover flange includes a front wall section 26, a rear hinge wall section 27, and a pair of connecting side wall sections 28.

The top wall section 25 uniformly slopes or curves downwardly toward the flange along three edges thereof, i. e., the front and two side edges. Along the rear edge of the cover the top wall section extends straight out thus producing in effect a raised rear edge indicated at 29. Into this raised rear edge, each side edge of the cover merges along a curved line and this produces a curved cam surface or fulcrum shoulder 31 along each side of the cover.

The front wall section 26 of the cover is formed with an outwardly extending locking node or projection 34 which engages over the body node 21 when the cover is in closed position on the box. These engaged nodes lock the cover against accidental opening. The rear wall section 27 of the cover is formed with a hinge lug 35 which extends down between the spaced body hinge lugs 22. This hinge lug carries a wire pintle 36 the outer ends of which extend into and operate within the elongated body hinge lugs 22.

When the cover is in closed position on the body the inside surface of the dome-shaped top wall section 25 rests on the top or terminal edge 19 of the body front and side wall sections 16, 18 as shown in Fig. 3. It will be noticed in this position that the cover cam surface 31 and the raised rear edge of the cover are above and clear of the back of the body terminal edge. The projecting ends of the hinge pintle 36 are also in the upper part of the elongated body hinge lugs 22 and the cover locking nodes 21, 34 are engaged in locking position.

To open the box it is merely necessary to pinch the cover and body members together along their rear or hinge edges. Such a pinching action presses the raised edge 29 of the cover down toward the rear of the terminal edge of the body rear wall section 17. The floating hinge permits this vertical movement, the ends of the pintle 36 moving down toward the bottom of the elongated body hinge lugs 22.

During such hinging movement between body and cover, the cover cam surfaces 31 rock on the rear part of the terminal edges of the body side walls as the front of the cover lifts up, the cam surfaces acting as fulcrums. Rocking of the cover on the box raises its front edge away from

the body and disengages the locking nodes 21, 34, thus bringing the cover into a released and partially opened position as shown in Fig. 4. Complete opening of the cover may now be effected by merely grasping the released front edge thereof and moving it upwardly.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

A hinge cover tablet box and the like, comprising a rectangular body member having upstanding front, rear and side walls with their top edges substantially in a single plane, a rectangular cover member having depending walls telescoping

over said body walls and connected by a top wall, said cover top wall at its junction with the depending cover side wall being bent downwardly towards the top edge of the body side wall from 5 a point adjacent the rear corner of the box cover towards the longitudinal center of the box to provide a gradually curved fulcrum shoulder which merges into a straight line of contact between cover top wall and top edge of the body side wall 10 when the box is closed, and a floating hinge connection between the rear walls of said members permitting vertical movement between said hingedly connected members, whereby a pinching pressure applied to either rear corner of the members 15 releases said straight line contact and rocks the cover member along said gradually curved shoulder upon the top edge of the body side wall to initially separate the respective front walls of said members and raise said cover into open position.

GEORGE C. ERB.
